BOTTLE CAP

Charles P. Hennon, Weslaco, Tex.

Application December 8, 1950, Serial No. 199,891

2 Claims. (Cl. 215—46)

1

This invention relates to bottle caps, and more particularly to bottle caps of the type having means for removing the cap from the top of a bottle without the use of any separate implement.

A main object of the invention is to provide a novel and improved bottle cap of the type having lever means for removing the cap from the top of a bottle, the improved cap being simple in construction, being positive in operation, and being manufacturable from a single piece of metal.

A further object of the invention is to provide an improved bottle cap of the crimped type provided with means for removing the cap from the top of a bottle without the use of a separate implement, the improved cap being inexpensive to manufacture, being quickly and easily removed when desired, and being easily manipulated when removal thereof is desired.

Further objects and advantages of the invention will become apparent from the following description and claims, and from the accompanying drawings, wherein:

Figure 1 is a front elevational view of an improved bottle cap according to the present invention shown mounted on the top of a bottle;

Figure 2 is a vertical cross-sectional view taken on the line 2—2 of Figure 1;

Figure 3 is an enlarged cross-sectional detail view taken on line 3—3 of Figure 2;

Figure 4 is a cross-sectional view taken on line 4—4 of Figure 2, showing the main body of the cap in bottom plan view, a portion of the cork of the cap being broken away and the bottle being omitted;

Figure 5 is a side elevational view showing the improved bottle cap of Figure 1 with its movable segment bent upwardly for removal of the cap from the top of a bottle.

Referring to the drawings, the improved bottle cap is designated generally at 11 and comprises a disc-shaped top wall 12 which is formed with a depending annular skirt 13 formed with the usual crimped elements 14 for clampingly securing the disc-shaped body member 12 to the top bead 15 of a bottle 16. The depending skirt 13 is formed with diametrically opposed slits 17, 17, said slits extending a substantial distance from the free lower edge of the skirt 13 and preferably terminating adjacent to the periphery of the disc-shaped top wall 12.

Designated at 18 is a depending tongue integrally formed with the bottle cap, said tongue being spaced substantially midway between the slits 17, 17 and merging with the segment at

5 one side of said slits through a radial, relatively narrow corrugation 19 of substantial height. As shown in Figures 2, 4 and 5, the radial corrugation 19 forms a continuation of the top end of the depending lever 18 and said radial corrugation extends inwardly and terminates substantially at the center of the disc-shaped top wall 12. As further shown in Figure 3, the side walls of the corrugation 19, shown at 20, 20, may be substantially in face-to-face contact, whereby, said corrugation is relatively narrow in width but has substantial rigidity with respect to vertically applied forces.

The bottle cap thus far described is stamped 15 from a single piece of metal and may be fabricated by a simple combination stamping and shearing operation.

Designated at 21 is a conventional cork stopper or pad secured to the bottom surface of the disc-shaped top wall 12 in the usual manner.

The bottle stopper is placed on the top of a bottle by the usual method when the bottle is filled at the bottling plant. When the user desires to remove the cap 11, he merely grasps the 25 lower end of the depending lever 18 and rotates the lever clockwise, as viewed in Figure 2, thereby transmitting torque through the rigid corrugation 19 to the bendable section of the bottle cap associated therewith, whereby said bendable section is bent upwardly with respect to the other section of the cap, as shown in Figure 5. Such upward bending is permitted by the provision of the diametrically opposed slits 17, 17. With the cap bent in the manner shown in Figure 5, the cap may be readily removed from the 30 top of the bottle and discarded.

If so desired, the cap may be replaced on the top of the bottle and restored to covering relation with respect to the bottle top by rotating 40 the depending lever 18 downwardly to engage the cap section associated therewith with the top bead of the bottle.

While a specific embodiment of an improved bottle cap of the lever type has been disclosed 45 in the foregoing description, it will be understood that various modifications within the spirit of the invention may occur to those skilled in the art. Therefore, it is intended that no limitations be placed on the invention except as defined by the scope of the appended claims.

What is claimed is:

1. A bottle cap comprising a disc-shaped top wall, a depending annular skirt formed on said top wall and having diametrically opposed slits 50 extending a substantial distance from the free

lower edge of the skirt, defining a pair of sections bendable relative to each other, an upstanding rib projecting transversely from the portion of said top wall of one of said sections midway of said slits and extending from the diametral line joining said slits to the adjacent portion of said skirt, and a depending lifting tongue arranged exteriorly of and merging with said skirt portion and having its top merging with said rib.

2. A bottle cap comprising a disc-shaped top wall, a depending annular skirt having diametrically opposed slits extending a substantial distance from the free lower edge of the skirt and defining a pair of sections bendable relative to each other, a pair of upstanding flanges lying in side by side relation and joined adjacent the upper edges projecting transversely from the portion of said top wall of one of said sections midway of said slits and extending from the diametral line joining said slits to the adjacent portion of said skirt, and a depending lifting

tongue arranged exteriorly of and merging with said skirt portion and having its top merging with said flanges.

CHARLES P. HENNON.
